(57) **CLAIM**

The ornamental design for an OLED luminaire, as shown and described.

DESCRIPTION

FIG. 1 is a bottom perspective view of an OLED luminaire showing my new design;

FIG. 2 is a top perspective view thereof;

FIG. 3 is a side elevational view thereof; the other three sides being identical thereto;

FIG. 4 is a top plan view thereof; and,

FIG. 5 is a bottom plan view thereof.

"OLED" means Organic Light-Emitting Diode. The characteristic feature of the design resides in the overall shape of the OLED luminaire. The body of the OLED luminaire can be transparent, translucent, or opaque; or different portions of the OLED luminaire body can be transparent, translucent, or opaque.

The broken line showing of OLED light sources on the bottom of the luminaire, and the broken line showing of suspension elements for the OLED luminaire, are provided for illustrative purposes only and form no part of the claimed design. The broken line squares on top of the luminaire shown in FIGS. 2-4 represent the bounds of the claimed design with the unshaded areas inside the squares forming no part of the claimed design.

1 Claim, 4 Drawing Sheets

FIG. 2

FIG. 3

FIG. 4
